(57) **CLAIM**

I claim the ornamental design for a collapsible accessory basket, as shown and described.

DESCRIPTION

FIG. 1 is perspective view of the collapsible accessory basket wherein the dashed lines depict sewing.

FIG. 2 is a front view of the basket.

FIG. 3 is a rear view of the basket.

FIG. 4 is a right side view of the basket (the left side view being a mirror image of the right side view); and,

FIG. 5 is a top view of the basket (the bottom view being a mirror image of the top view).

The circular features illustrated in FIGS. 1, 2, and 3 represent a type of surface pattern.

The broken lines showing in FIGS. 1-5 represent stitching.
